W. J. MC CUTCHEON,

Trunk,

No 14,879.

Patented May 13, 1856.

UNITED STATES PATENT OFFICE.

WILLIAM J. McCRAKEN, OF ROCHESTER, NEW YORK.

IMPROVEMENT IN WARDROBE-TRUNKS.

Specification forming part of Letters Patent No. 14,879, dated May 13, 1856.

To all whom it may concern:

Be it known that I, W. J. McCRAKEN, of Rochester, in the county of Monroe and State of New York, have invented a new and useful Improvement in Trunks, which I term a "Wardrobe Trunk;" and I do hereby declare that the following is a full, clear, and exact description of the same, reference being had to the annexed drawings, making a part of this specification, in which—

Figure 1 is a transverse vertical section of my improvement represented in a closed state in black and in an open and partially-open state in red and blue. Fig. 2 is a front view of same, represented in an open state, one of the end pieces of the upper part of the trunk and one of the end pieces of the sliding box being bisected.

Similar letters of reference indicate corresponding parts in the two figures.

My invention consists in the peculiar construction of the trunk, as will be hereinafter fully shown and described, whereby the trunk may with the greatest facility be converted into a wardrobe and space still allowed in the lower part of the trunk for receiving such articles that do not require to be hung on hooks.

To enable those skilled in the art to fully understand and construct my invention, I will proceed to describe it.

A represents the body of the trunk, which is of the usual form and divided as usual into the parts *a* *b*, connected by hinges *c* at the back.

The lower part *b* of the trunk has the usual box *B*, fitted within it, and to the upper part of *b* a supplementary lid *C* is attached by hinges *d*. To the under side of the lid *C* a pocket *D* is secured.

Within the upper part *a* of the trunk a sliding box *E* is placed. This box has a handle *e* on its outer end, which end forms the front side of the upper part of the trunk. A hook *f* is attached to the inner end of the box, which hook is fitted in a staple *g* in the inner side of the back part of the part *a* of the trunk, said hook securing the box within the part *a*. (See Fig. 1.) The box *E* is not closed at its inner end, and the lower or under side of the box is formed of two doors *h* *h*, which are hinged to the box. The upper side of the box has hooks *i* attached to it. The up-

per side of the box *E* has a slide *j* fitted to it and the two doors *h* *h* have parts *k* *k* jointed to them, so that when the box *E* is withdrawn from the part *a* of the trunk it may be lengthened by shoving out the slide *j* and turning down or outward the parts *k* *k* at the lower ends of the doors *h* *h*.

To the inner side of the upper part *a* of the trunk there are attached by joints or hinges strips *l* *l*, one at each end of the part *a*. The outer ends of these strips are provided with dovetails *m*, as shown clearly in blue, Fig. 1.

The under side of the part *a* of the trunk has a lid *F* attached to it by hinges *n*, and a support *o* is attached to the back part of said lid by hinges *p*.

When the trunk is closed, the several parts are in the position as shown in Fig. 1, the box *E*, being within the upper part *a* of the trunk and secured therein by the hook *f*, the doors *h* *h* being closed and locked and the slide *j* secured in proper position by bolts.

When the part *a* of the trunk is raised in a horizontal position, the lid *F* may be raised, the doors *h* *h* opened, and articles placed within the box *E*. Thus it will be seen that nearly the same room is obtained in this trunk, when used as a trunk, as in the ordinary ones. The trunk is converted into a wardrobe by removing the hook *f* from the staple *g* and then withdrawing the box *E* from the part *a* of the trunk. The strips *l* *l* are then raised to a vertical position, the dovetails *m* being fitted in corresponding recesses in the ends of the box *E*. The strips *l* *l* project some distance above the box *E*; but by shoving down the slide *j* and securing it by the bolts *g*, and turning down the parts *k* *k* of the doors *h*, the box *E* will be lengthened and form a continuation of the part *a* of the trunk. The parts when thus arranged will form a wardrobe, clothes being hung on the hooks *i*.

The lower part *b* of the trunk may be used as usual for receiving such articles of clothing as are not liable to be injured by being folded.

The lid *C* may be provided with a lock and also the doors *h*.

The above improvement is a valuable one, for persons when traveling and stopping at hotels are often compelled to keep their clothes in their trunks. Ladies' dresses are particularly liable to be creased or injured by

being kept folded, and gentlemen's clothing, broadcloth coats and pants, will also become creased.

By my invention the trunk may be readily converted into a wardrobe and the clothes may be locked or secured therein and be equally as secure as if locked within an ordinary trunk.

The lid F, by being raised and supported by the support o, may be used as a writing-desk, as shown by the black dotted lines, Fig. 1.

What I claim as my improvement, and desire to secure by Letters Patent, is—

1. The construction and arrangement of the

supporting-strips l l in the portion of the trunk a for uniting the sliding portion of the wardrobe E to the part a of the trunk, as and for purposes mentioned in the foregoing specification.

2. The construction and arrangement of the lid F and supporter o, as combined and arranged with the portion of the trunk a, for purposes mentioned in the foregoing specification.

WM. J. McCRAKEN.

Witnesses:

WM. TUSCH,

JAMES F. BUCKLEY.
